US00D608316S

(12) **United States Design Patent**
Quiros et al.

(10) **Patent No.:** US D608,316 S
(45) **Date of Patent:** ** Jan. 19, 2010

(54) **TELEPHONE**

(75) Inventors: **Jose Quiros**, Colorado Springs, CO (US); **Hans Henrik Petersen**, Cambridge (GB); **Andrew Robert James Russell**, Bourn (GB); **Jamie Kevin Widdows**, Cottenham (GB)

D302,274 S 7/1989 Fujita et al.
D303,114 S 8/1989 Danielson et al.
D303,115 S 8/1989 Hart et al.
D303,665 S 9/1989 Ohta et al.
D304,338 S 10/1989 Sermon

(73) Assignee: **TeleMatrix, Inc.**, Colorado Springs, CO (US)

(Continued)

(**) Term: **14 Years**

(21) Appl. No.: **29/326,003**
